UNITED STATES PATENT OFFICE.

ROBERT T. GILLESPIE, OF ROCHESTER, PENNSYLVANIA.

INK-WELL.

SPECIFICATION forming part of Letters Patent No. 789,534, dated May 9, 1905.

Application filed August 22, 1904. Serial No. 221,746.

To all whom it may concern:

Be it known that I, ROBERT T. GILLESPIE, a citizen of the United States, residing at Rochester, in the county of Beaver and State of Pennsylvania, have invented certain new and useful Improvements in Ink-Well, of which the following is a specification, reference being had therein to the accompanying drawings, forming part of this specification, in which—

Figure 1 is a vertical sectional view of my improved ink-well. Fig. 2 is a similar view showing a modified construction provided with two oppositely-located delivery-necks. Fig. 3 is a similar sectional view showing a vertically-arranged delivery-neck. Fig. 4 is a horizontal section on the line IV IV of Fig. 3. Fig. 5 is a similar sectional view showing a construction provided with a removable cover for the entire area of the reservoir. Fig. 6 is a similar view showing the delivery-neck provided with an adjustable cover. Fig. 7 is a partial detail sectional view of the same construction, showing the cover raised and fixed in open position. Fig. 8 is a perspective detail view of the spring-controlled cover for the neck. Figs. 9, 10, and 11 are detail views in perspective of different forms of neck-floats.

My invention consists of improvements in the class of ink-wells of the class wherein a main reservoir is provided for the ink and a laterally-disposed delivery-neck is arranged in communication with the reservoir at its base and provided with means for covering the ink. The covering means consists of an automatically-adjustable float adapted to rest upon the surface of the ink in the neck and provided with a central reduced cavity whereby the ink is delivered in limited quantity to the pen-point merely by insertion.

Referring to the drawings, 2 is the main ink-well body, preferably rectangular in form, although it may be circular or otherwise formed, as desired, provided with a reservoir-cavity 3, adapted to contain the main body of ink and provided with a removable cover 4. At one side or in front of the well is an independent neck-chamber 5, communicating with the main reservoir 3 at the bottom through a port-opening 6, so that the

ink in the reservoir and neck will always be maintained at the same level. The neck preferably inclines forwardly, as shown, at any suitable angle, to facilitate insertion of the pen-point, and in the neck is mounted a float 7, of cork or other suitable buoyant material, fitting freely within the neck-chamber to facilitate easy movement. The float is provided with a central cavity or channel 8, terminating at the top in an outwardly-flaring orifice 9 of sufficient size to admit the point of the pen, the channel 8 being so reduced that the tip of the pen only enters it. This construction is of advantage in indicating to the operator not only when the tip has been inserted 65 into the channel, but also indicating the moment of contact with the float, so as to gage the downward pressure thereof in order to sufficiently submerge the pen-point.

For the purpose of preventing the float 70 from rotating the neck-chamber is preferably made square or of other suitable form in cross-section, this construction being of advantage in always maintaining the long lip of the float in front when used with a slanting neck having a horizontal top, as in Figs. 2, 5, and 6. Otherwise, however, the float may be made to correspond with the upper terminal of the neck if extended as in Fig. 1, and the float and neck may also be made circular in form, 80 as indicated in Fig. 11.

For the purpose of simplifying the construction of the well when made of glass or other material by means of plunger mechanism the form shown in Figs. 5 and 6 may be employed, 85 wherein the full area of the reservoir is continued to the top, and a cover 10 of corresponding area, provided with interfitting lips 11, is used. In other respects, however, the construction and mode of operation are the 90 same. For the purpose of covering the top of the neck I employ a cap 12, pivotally connected at 13 with a base 14, cemented or otherwise secured to the top of the well-body, as shown. A spring 15 is secured underneath 95 said base in a cavity formed in the body of the well, which presses upwardly against a double flat-faced shoulder 16, forming a portion of the cover, so as to exert pressure positively against said shoulder to hold the cap down in 100

position or upwardly, as shown in Figs. 6 and 7, respectively.

In Fig. 2 the well is shown provided with two oppositely-arranged necks, adapting it to use on a double desk, each neck communicating with the common well 3' and being provided with independent floats, as shown.

The operation will be readily understood from the foregoing description.

10. The device is very compact and simple in construction, the indicating-float is of great assistance to the operator in filling the pen, the inclination of the neck allows the pen to be inserted in a natural direction, while the 15 float also covers the ink and practically prevents evaporation or contamination of the ink.

The well is especially adapted to incorporation with any suitable receiving or holding receptacle having openings or apertures in the

20 front or side—as, for instance, a desk-drawer—through which the pen may be inserted to reach the neck. The float in such cases immediately indicates the depth to which the pen should be inserted.

25 Changes or variations may be made by the skilled mechanic in the design, proportions, or other details of the invention; but all such are to be included within the scope of the following claims.

30 What I claim is—

1. An ink-well provided with a main reservoir-chamber, a neck-chamber having a polygonal cross-area communicating with the reservoir-chamber at the bottom, and a freely-35 movable float fitting loosely in the neck-chamber, provided with a reduced central cavity flaring outwardly at the top, substantially as set forth.

2. An ink-well consisting of an integral 40 body portion of suitable material provided with a main reservoir having a removable top,

an inclined neck provided with a supply-chamber communicating with the main reservoir at the bottom, and a freely-movable float mounted in the neck-chamber and provided with a 45 central reduced opening and a flaring pen-insertion opening at the top, substantially as set forth.

3. An ink-well consisting of an integral body portion of suitable material provided 50 with a main reservoir having a removable top, an inclined neck provided with a supply-chamber communicating with the main reservoir at the bottom, and a freely-movable float mounted in the neck-chamber and provided with a 55 central reduced opening and a flaring pen-insertion opening at the top, the neck-chamber and float being so formed in cross-section as to prevent rotation of the float, substantially as set forth.

4. The combination with an ink-well having a main reservoir and an inclined neck-chamber communicating therewith at the bottom with a perforated float mounted in the neck-chamber: of a spring-controlled cover for the 65 neck-chamber, substantially as set forth.

5. The combination with an ink-well having a main reservoir and an inclined neck-chamber communicating therewith at the bottom with a perforated float mounted in the neck-chamber: of a base secured to the ink-well 70 body and provided with a pressure-spring, and a cover for the neck-chamber pivoted thereto and provided with spring-bearing shoulders adapted to make contact with the spring, substantially as set forth.

In testimony whereof I affix my signature in presence of two witnesses.

ROBERT T. GILLESPIE.
